UNITED STATES PATENT OFFICE.

CHARLES ANDREWS, JR., OF ROCKFORD, ILLINOIS, ASSIGNOR TO ANDREWS WIRE & IRON WORKS, OF ROCKFORD, ILLINOIS, A CORPORATION OF ILLINOIS.

BAG HOLDER.

Application filed February 10, 1917. Serial No. 147,875.

To all whom it may concern:

Be it known that I, CHARLES ANDREWS, Jr., a citizen of the United States, residing at Rockford, in the county of Winnebago 5 and State of Illinois, have invented certain new and useful Improvements in Bag Holders, of which the following is a specification.

One of the objects of my invention is to provide an improved bag holder of ample 10 strength and durability for supporting a strainer or the like and which may be collapsed into very compact form so that it will occupy but little space and may consequently be very easily and conveniently 15 handled, packed and transported.

Another object is to provide as an article of manufacture a bag holder of such simple design that it may be used with different sized bowls and vessels and which is constructed so simply that it may be produced at a comparatively low cost.

Referring to the drawings,

Figure 1 is a view in elevation of one side of a bag holder embodying my improvements and being associated with a bowl, showing a portion of the bowl and bag in section;

Fig. 2 is a view in elevation of another side of the bag holder and bowl;

Fig. 3 is a top view of the bag or holder and the bowl, with the bag removed;

Fig. 4 is a view of the bag holder detached from the bowl and collapsed into compact form.

In this invention, I have contemplated the provision of improvements consisting, generally stated, of legs adapted to extend upwardly on opposite sides of a bowl or other open top vessel and equipped a substantial distance above the top of the bowl 35 with bag supporting means, which is adapted to detachably receive and support a fabric bag, so that the latter will depend through said supporting means between the

legs and be sustained wholly above the top 45 of the vessel. While my improvements are intended for supporting bags of different kinds for various purposes I have in the present instance illustrated it in connection 50 with holding a bag-like strainer. Accordingly, fruit, jelly or other ingredients to be strained may be placed in the bag and left to percolate slowly therethrough into the vessel and the latter may be filled without 55 the contents thereof interfering with the

bag, since the same is suspended a sufficient distance above the top of the vessel. The vessel in connection with which I have illustrated my improvements is a well known form of straining bowl. The legs constituting a part of the strainer support are, in the present instance, two in number and each formed of a single strand of wire. These legs designated in general by reference character 6 are shaped at their lower ends to detachably engage and be supported by the rim of the bowl 5 on diametrically opposite sides thereof and extend upwardly therefrom and are pivotally attached at their upper ends to a ring member 7. In 70 the particular form illustrated, the ends 8 of the wire strand forming one leg member are inserted into a tubular attaching or pivot piece 9, from opposite ends thereof, and this tubular piece is suitably secured to 75 the ring member 7 as by means of extensions 11 from said piece 9 spot welded to the inner side of the ring member in the manner shown. This is a simple way of pivotally securing the legs to the ring member 7, but any suitable pivotal connection may be provided for the purpose. The portions of the wire strand adjacent to the ends 8 are shaped to provide stops 12 which are adapted by contact against the periphery 80 of the ring member 7 to limit outward swinging movement of the legs on their pivot ends 8. The lower end of each leg is shaped to provide hooked portions 13 which fit over the rim of the bowl, engaging beneath the peripheral edge thereof, as at 14, and being joined and held in spaced relation by a cross portion 15. Leg members formed in this manner may be produced very cheaply and serve to detachably support a strainer-supporting means such as 90 the ring 7 in a very substantial manner considering the purpose of the article.

The strainer proper may be in the form of a fabric bag 20 having its edge 16 turned over a ring 17 so that when the bag is inserted through the ring member 7 the peripheral edge of the bag stiffened by the ring 17 will rest upon the ring member so as to properly associate the bag with its 100 supporting means. By constructing and supporting the strainer in this manner it may be easily removed from and placed upon its supporting means.

It will be noted by reason of the pivotal 110

connection of the leg members to the bag supporting means the leg members may be accommodated to bowls or vessels of various sizes. Also, by reason of the particular pivotal arrangement and the construction of the leg members, the bag holder may be collapsed into compact form by swinging the leg members inwardly toward each other and passing one of them intermediate and beyond the spaced members of the other until the parts are in substantially parallel relation, so that they make a compact bundle, as shown in Fig. 4. My improvements thus provide a bag holder which is supported wholly and centrally above an open top vessel by leg members on opposite sides of the bag which serve to support the latter in a very substantial manner. While I have shown a particular mechanical embodiment it should be understood that various changes in the construction and design of the parts may be resorted to without departing from the spirit and scope of the invention as expressed in the appended claims:

25 I claim:

1. A bag holder comprising a holder for the mouth of the bag, members for supporting the holder centrally above an open top receptacle, each member formed of a single 30 length of wire shaped to provide socket por-

tions adapted to seat on the rim of the receptacle at circumferentially spaced points thereon, a cross portion connecting and holding said socket portions in spaced relation, and an upright leg extending from each 35 socket portion to the holder and terminating in a stop portion and a pivot end, and means pivotally connecting the said ends to the holder, the stop portions being adapted to bear against the holder when the lower ends 40 of the leg members are swung outwardly and the leg members adapted to swing inwardly into close relation to the holder.

2. A bag holder comprising a holder for the mouth of the bag, wire leg members for 45 supporting the bag centrally above an open-top receptacle, each member formed of a single piece of wire bent to provide a pair of socket-like portions adapted to seat on the rim of said receptacle and having a 50 medial portion adapted to hold said socket like portions in laterally spaced relation, the end portions of the wire extending upwardly from said socket portions in laterally spaced relation to the holder and terminating in laterally bent pivotal ends, and means pivotally connecting said ends to the 55 holder.

CHARLES ANDREWS, JR.
